(No Model.)

W. E. GOOD & C. O. LINDROTH.
PISTON.

No. 451,478.

Patented May 5, 1891.

UNITED STATES PATENT OFFICE.

WILLIAM E. GOOD AND CARL OSKAR LINDROTH, OF PHILADELPHIA, PENNSYLVANIA, ASSIGNORS TO THE SOUTHWARK FOUNDRY AND MACHINE COMPANY, OF SAME PLACE.

PISTON.

SPECIFICATION forming part of Letters Patent No. 451,478, dated May 5, 1891.

Application filed November 20, 1890. Serial No. 371,983. (No model.)

To all whom it may concern:

Be it known that we, WILLIAM E. GOOD and CARL OSKAR LINDROTH, both of the city and county of Philadelphia, State of Pennsylvania, have invented a certain new and useful Improved Piston, of which the following is a true and exact description, reference being had to the accompanying drawings, which form a part of this specification.

10 Our invention relates to the construction of pistons and has for its object to provide a piston of improved construction and of which the outer ring, called the "bull-ring," can be readily removed and adjusted without 15 separating the piston proper from the rod to which it is attached. This is especially important in compound engines in which the high and low pressure cylinders are arranged in line with each other and with their pistons 20 secured to the same rod.

The novel features of our invention will be best understood as described in connection with the drawings in which they are illustrated, and in which—

25 Figure 1 is a side elevation showing a high and low pressure cylinder arranged in line with each other and with their pistons secured to the same piston-rod. Fig. 2 is a face view of the piston with the follower-plate removed. Fig. 3 is a cross-section taken on the line 1 2 of Fig. 2, and showing the follower-plate in place. Fig. 4 is a sectional view taken on the line 3 4 of Fig. 3; Fig. 5, a sectional view taken on the line 5 6 of Fig. 4, and Fig. 35 6 a side view showing how the parts of the bull-ring are fastened together.

A and B are respectively the low and high pressure cylinders of the engine; C, the space between the two cylinders; D, the piston-rod; 40 E and E', pistons situated, respectively, in the high and low pressure cylinders.

The piston is made up of the piston proper or piston center, which is secured to the piston-rod, an outer ring, called the "bull-ring," 45 which is secured around the periphery of the piston center, and which we preferably form in sections, so that it can be removed readily from the center, and finally the packing-rings, which are secured in grooves in the 50 bull-ring.

In the drawings we have indicated the piston center by the letter F, f being the central hole in which the piston-rod is secured, f' a flange projecting beyond the face of the piston center on one edge, f² a recess formed in the opposite edge to receive a follower-plate, f³ a threaded screw-hole, and f⁴ f⁴, &c., transverse grooves formed across the face of the piston center to receive keys or wedges.

G is the outer or bull ring of the piston, 60 which is secured to the face of the piston center and should have a face of the same breadth as the piston center. In the outer face of the bull-ring grooves g g are formed to receive packing-rings, and the inner face of the bull-ring is provided for inwardly-projecting lugs or flanges g' g', &c., which fit between the flange f' on one side and the follower-plate on the other. In these inwardly-projecting lugs key-grooves g³ are formed, so that they will 70 register with key-grooves f⁴ in the piston center.

An important feature of the construction of the bull-ring is that it should be made in sections, as shown, lugs g² g² being provided 75 at the edge of each section, so that abutting sections can be bolted together, as shown. It is sufficient that the bull-ring should be formed in two sections, and this plan is illustrated in the drawings.

H is the follower-plate which fits into the recess f² and has a projecting flange h, which extends above the face of the piston-center surface, together with the flange f', to hold the bull-ring in place upon the center. The 85 follower-plate is held in position by means of screws I, which pass through it and enter the threaded perforations f³ in the piston center.

In order to prevent the bull-ring from turning on the center and also to provide means 90 for adjusting it from time to time, so as to keep the piston-rod in the center of the cylinder, we provide keys or wedges J, adapted to enter the registering grooves f⁴ g³, the adjustment preferably being effected by means 95 of the insertion or removal of thin plates or shims, indicated at K. These shims and keys are inserted before the follower is secured to the piston-center and are held in place by the said follower.

By carrying the face of the bull-ring over the follower and the flange f'' we are enabled to secure the packing-rings (indicated by the letter L) close to the outer edge of the piston, thus securing a broad bearing surface and insuring that the said surface shall not diminish with the adjustment of the wedges.

Having now described our invention, what we claim as new, and desire to secure by Letters Patent, is—

In a piston, the combination, with a piston center, as F, having a flange f'' on one edge

and key-grooves f^4 formed along its face, of a follower H, having a flange h , a divided bull-ring G, adapted to fit between and over flanges f'' and h , grooved to receive packing-rings, and having also transverse grooves g^3 , registering with grooves f^4 , and adjusting-keys J, adapted to fit in grooves g^3 g^4 .

WILLIAM E. GOOD.

C. O. LINDROTH.
